UNITED STATES PATENT OFFICE.

ROBERT H. REED, OF EASTON, PENNSYLVANIA, ASSIGNOR TO INGERSOLL-RAND COMPANY, OF JERSEY CITY, NEW JERSEY, A CORPORATION OF NEW JERSEY.

COMBINED TAR EXTRACTOR AND GAS EXHAUSTER.

Application filed April 30, 1924. Serial No. 709,945.

To all whom it may concern:

Be it known that I, ROBERT H. REED, a citizen of the United States, and a resident of Easton, county of Northampton, and 5 State of Pennsylvania, have invented a certain Combined Tar Extractor and Gas Exhauster, of which the following is a specification accompanied by drawings.

This invention relates to blowers and 10 pumps and possesses features of general application which are more particularly adapted for use in apparatus for exhausting and pumping gas which contains in suspension heavier substances, such as tar and the like. 15 In the process of manufacturing illuminating gas by distillation of coal and other substances, it is usually found that slight quantities of tar are carried over in suspension by the gas which later separate and 20 become troublesome in that they collect on the walls of the pipe lines and conduits by which the gas is conveyed.

It is an object of this invention to separate the tar from the gas by which it has 25 been held in suspension, preferably by means of a separator integrally formed with the blower or exhauster. This object is accomplished by the invention in its improved form by accelerating the gas to a high velocity and passing it through devious paths 30 to change the direction of flow, whereby the tar is thrown out of suspension by its tendency to resist a change of direction due to its greater mass.

35 The invention will be more clearly understood by reference to the following description taken in conjunction with the accompanying drawings, in which—

Figure 1 is a vertical longitudinal section 40 of part of a blower embodying the tar separating means, this section being taken along the line 1—1 of Figure 2 looking in the direction of the arrows, and

Figure 2 is a cross section of the blower 45 along the line 2—2 of Figure 1 looking in the direction of the arrows.

The exhauster includes a casing A within which are housed a plurality of impellers B, C and D rigidly mounted on a shaft E for 50 rotation therewith. Gas is adapted to be drawn from a supply pipe F through an inlet G to the first stage impeller B by which it is compressed and passed on through intermediate pressure chambers H, J and K to the 55 successive higher stage impellers C and D.

The shaft E is provided with a suitable journal L and water seal O at the inlet and discharge end of the shaft to prevent the escape of gas to atmosphere along the shaft.

Each of the impellers is provided with a diffuser, those corresponding with the impellers C and D being shown at P and Q respectively. The diffuser R which cooperates with the impeller B is formed by a casting head S and the casing A, there being 60 provided a flange T forming one side of the diffuser.

In accordance with the practice of this invention the tar carried in suspension by the gas is separated by centrifugal action, 70 that is to say the gas and the tar are brought to a high velocity and then passed through a number of relatively sharp turns which causes the heavy liquid or semi-solid matter to be thrown outwardly and to be separated 75 from the gas, which, being lighter, is readily deflected.

In this embodiment the separation is arranged to take place at the first stage of compression of the gas. It is understood, 80 however, that each or any stage may be equipped with similar separating apparatus. High velocity is imparted to the gas entering the blower by means of the impeller B. The gas is projected into the diffuser R 85 wherein its velocity is substantially maintained by means of vanes U, which are triangular in form to partly fill the diffuser throat R for the purpose of maintaining a substantially constant cross section from the 90 entrance to the exhaust of the diffuser. The velocity of the gas leaving the diffuser R is therefore substantially the same as its velocity on entering. At the end of the diffuser R the path of the gas takes a sharp 95 turn as at V, and adjacent this point there is provided a passageway W leading to an annular chamber X. The tar, being relatively heavy as compared with the gas, will be projected radially outward through the 100 passageway W and collect in the chamber X.

The tar collecting in the chamber X collects by gravity in a sump Y from which it may be withdrawn through a suitable drain Z. After the gas is turned at B the flow is 105 kept in a circular path so as to throw out any heavy matter which may still be in suspension to collect on the inner wall of the casing head S whence it may drop down into annular chambers a and b, which are sepa- 110

rated by a rib *e* to provide dead space for the collected tar. The gas then passes transversely across the diffuser *R* through apertures *c* in the vanes *U* into the intermediate pressure chamber *H*.

Toward the lower side of the casing head *S* the outermost chamber *a* is separated from the chamber *b* by a partition *d* so as to prevent the current of gas from picking up the tar as it drops to the bottom. Also in the lower half of the casing head *S* the chamber *a* communicates directly with the annular chamber *X* so that the tar may drop freely into the sump *Y*.

I claim:

1. A combined exhauster and tar extractor for gas comprising a casing, an impeller rotatably mounted within said casing, a diffuser, means for passing the gas from said diffuser through a plurality of sharp turns including vanes disposed in said diffuser provided with apertures extending

transversely across said diffuser and chambers adjacent such sharp turns for collecting the tar centrifugally separated from said gas.

2. A combined exhauster and tar extractor for gas comprising a casing, an impeller rotatably mounted within said casing, a casing head, a diffuser formed integrally with said casing and said casing head, an annular chamber in said casing head adjacent said diffuser to receive tar centrifugally separated from said gas, means for guiding the gas through a plurality of sharp turns including said casing head and vanes disposed in said diffuser having apertures extending transversely across said diffuser, tar collecting chambers adjacent such sharp turns and a sump associated with all of said chambers.

In testimony whereof I have signed this specification.

ROBERT H. REED.
